CONDENSER

Application filed December 31, 1926. Serial No. 158,191.

The present invention relates to variable condensers and inductances for use in radio and other circuits and particularly to sets of two or more condensers or inductances having tandem mechanical connection for simultaneous adjustment and control and having an auxiliary condenser or inductance for one or more of the tandem condensers or inductances for accurately correcting the characteristic value of one of such devices so that each of the units in a given tandem will have the same accurately adjusted value with respect to the other or others for any given adjusted position of the tandem group.

Various objects and advantages of the invention will be obvious from the following particular description of one form of apparatus embodying the invention or from an inspection of the accompanying drawing; and the invention also consists in certain new and useful features of construction and combinations of parts hereinafter set forth and claimed.

In the accompanying drawing there is shown for purposes of illustration one form of apparatus embodying the invention, in which

Fig. 1 is an elevation view showing somewhat diagrammatically an embodiment of the invention,

Fig. 2 is a plan view of a part of the apparatus illustrated in Fig. 1, and

Fig. 3 is a view taken along the line 3—3 of Fig. 2 and looking in the direction of the arrows.

In the use of variable electrical condensers in tandem in radio and other circuits with a single control for a plurality of condensers there is generally a difference in capacity between the different condensers for any given setting. This difference is usually compensated by connecting a small auxiliary condenser in multiple with that condenser having the lower capacity value but an adjustment made in this way is accurate or exact for only one position of the main compensated condenser and for other positions can at best be only an approximate correction. According to this invention there is connected in multiple with the main compensated con-

denser a small variable condenser which is mechanically connected with the variation control of said main compensated condenser in such manner that as the said main condenser is adjustably varied the said adjustable auxiliary condenser is also made to vary and to vary in values which will make the correction for any given position nearly or substantially exact.

In the drawing the base 1 and the front panel 3 support a variable condenser 4, the shaft 6 of which extends through said panel 3 and carries the adjusting knob 8 and the dial pointer 10. Connected to said shaft 6 by the insulating member 12 and axially aligned therewith is the shaft 14 of another variable condenser 16 supported by said base 1 and a panel 18 through which said shaft 14 extends. Back of said panel 18 is a third panel 20 which supports the auxiliary variable condenser 22 whose controlling shaft 24 is likewise supported by said panel 20.

Said shaft 24, whose axis, parallel to that of said shaft 14 but a little out of line therewith, is mechanically connected to said shaft 14 by an adjustable crank member 26 which extends radially from said shaft 14 and which has formed therein the radially extending slot 28 into which extends the pin 30 which projects from a sleeve 32 slidably mounted on a rod 34 extending radially from said shaft 24 and adjustably fixable thereon by means of the thumb screw 36.

Said condenser 4 has a connecting wire 38 from its stationary plates and the connecting wire 40 from the rotatable plates thereof. The rotor plates of said condensers 16 and 22 are connected together by the wires 42, 44 and the stator plates of these two condensers are connected together by means of the wire 46. While both sides of said condensers 4 and 16 are shown as being insulated from each other it is to be understood that either side of both of these can be grounded or connected to a common lead without departing from the present invention.

As indicated in dotted lines in Fig. 1, in some embodiments of the invention said shaft 24 is mounted to said panel 20 through the section 50 which is slidable in a slot 52 in panel 100

20 and held in place by a tongue 54 on each side of slide 50 and a slot 56 in the corresponding slot 52. A screw 60 mounted to section 50 and having a pair of adjusting nuts 62, 62 serves with the member 64 positioned between said nuts 62, 62 to adjust the position of said shaft 24 with respect to said shaft 14. By adjusting the position of said pin 30 along said slot 28 or of said shaft 24 by means 10 of said nuts 62, 62 the amount of increment or decrement in the value of the capacity of the parallel connected condensers 16 and 22 can be varied to suit the average difference in value between the said condensers 4 and 16 15 for different rotational positions of the rotors thereof, and a compensation for this difference can be obtained which is quite accurate for any position of rotation.

It is to be understood that while variable 20 condensers mechanically mounted in tandem have been described for the purpose of illustrating the invention other variable electric circuit regulating devices can be mounted in the same way. Such other devices or combinations are, for example, tandem sets of 25 variable inductances or loose couplers or condensers and loose couplers mounted in tandem and requiring correction of one of them to compensate for increments or decrements 30 of relative values resulting from variation of both together and for compensating for increments or decrements in rates of change of relative values.

While I have shown and described and have 35 pointed out in the annexed claims certain novel features of the invention, it will be understood that various omissions, substitutions and changes in the forms and details of the device illustrated and in its operation 40 may be made by those skilled in the art without departing from the spirit of the invention.

I claim:

1. In combination two variable condensers 45 mounted on a common adjusting shaft and an auxiliary variable condenser mounted with its controlling shaft parallel to and off the center of said first shaft and mechanically connected therewith through a slide 50 crank connection.

2. In combination two variable condensers mounted on a common adjusting shaft and an auxiliary variable condenser mounted with its controlling shaft parallel to and off 55 the center of said first shaft and mechanically connected for rotation therewith through an eccentric connection, whereby the eccentricity of said shafts causes said auxiliary condenser to move at a varying rate 60 with respect to said first mentioned condensers.

3. In combination two variable condensers having their rotor plates mounted on a common shaft, an auxiliary condenser for at 65 least one of said condensers, said auxiliary

variable condenser being mechanically connected for positive rotation with its associated condenser through an eccentric connection.

4. In combination two variable condensers 70 having their rotor plates mounted on a common shaft, an auxiliary variable condenser for at least one of said condensers, and an eccentric slide crank mechanically connecting said auxiliary variable condenser with its 75 associated condenser for rotation therewith.

5. In combination two variable condensers mounted on a common adjusting shaft and an auxiliary variable condenser mounted with its controlling shaft parallel to and off the center of said first shaft and mechanically connected therewith through an adjustable slide crank connection.

6. In combination two variable condensers mounted on a common adjusting shaft and an auxiliary variable condenser mounted with its controlling shaft parallel to and off the center of said first shaft and means for changing the distance of the shaft of said auxiliary condenser from that of its corresponding 90 main condenser.

7. In combination two variable condensers mounted on a common adjusting shaft and an auxiliary variable condenser mounted with its controlling shaft parallel to and off the center of said first shaft and mechanically connected therewith through a crank connection and means for changing the distance of the shaft of said auxiliary condenser from that of its corresponding main condenser. 100

8. In combination two variable condensers mounted on a common adjusting shaft and an auxiliary variable condenser mounted with its controlling shaft parallel to and off the center of said first shaft and mechanically connected for rotation therewith through an eccentric connection and means for varying the eccentricity of these two condensers. 105

9. In combination, a plurality of variable controlling elements for electric circuits, each of said elements comprising a stator and a rotor, the axes of two of said rotors being out of alignment but parallel, and a connection between said last named rotors which avails of the relative eccentricity thereof to effect 110 simultaneous movement of said rotors through different angles when one of said rotors is adjusted.

Signed at Hoboken, in the county of Hudson and State of New Jersey this 29th day of December, A. D. 1926.

LEROY J. BUTTOLPH.
